W. P. GRUNER.

CAN OPENER.

APPLICATION FILED FEB. 14, 1916.

Patented Oct. 17, 1916.

Inventor,
William P. Gruner.
By Bakewell & Churchills.

UNITED STATES PATENT OFFICE.

WILLIAM P. GRUNER, OF ST. LOUIS, MISSOURI.

CAN-OPENER.

1,201,456.

Specification of Letters Patent. Patented Oct. 17, 1916.

Application filed February 14, 1916. Serial No. 78,226.

To all whom it may concern:

Be it known that I, WILLIAM P. GRUNER, a citizen of the United States, residing at St. Louis, Missouri, have invented a cer-

5 tain new and useful Improvement in Can-Openers, of which the following is a full, clear, and exact description, such as will enable others skilled in the art to which it appertains to make and use the same.

10 This invention relates to can openers of the type that comprises a vertically-disposed member that is adapted to be forced downwardly into engagement with the head of a can, and a horizontally-disposed arm revolvably mounted on said member and provided with a knife blade or cutting device for severing the head of the can.

One object of my invention is to provide 20 a can opener of the general type referred to, which is so constructed that the can being opened will be centered and clamped securely in position before the cutting device on the swinging arm is forced down-

25 wardly through the head of the can, this being accomplished by mounting the cutter-carrying arm in such a manner that it can be moved vertically with relation to the member on which it is revolvably mounted.

30 Another object is to provide a can opener of the type just referred to, in which the cutter-carrying arm is so mounted that it will move upwardly automatically, and thus disengage the cutter from the head of

35 the can as soon as the operator releases said arm. And still another object of my invention is to provide a can opener of the type mentioned, in which the cutter-carrying arm is so mounted that the cutter 40 travels in a substantially vertical path when it penetrates the head of the can.

Other objects and desirable features of my invention will be hereinafter pointed out.

45 Figure 1 of the drawings is a perspective view of a can opener constructed in accordance with my invention. Fig. 2 is a side elevational view of the cutter-carrying arm and the can-holding member on which said arm is revolvably mounted; and Fig. 3 is a top plan view of the parts shown in Fig. 2.

50 Referring to the drawings, which illustrate the preferred form of my invention, A designates a base or supporting member on which a can is adapted to be arranged, as shown in Fig. 1; B designates a standard

projecting upwardly from said base and provided at its upper end with a laterally-projecting portion 1 that hangs over the base A, and C designates a vertically-disposed can-holding member that is adjustably mounted in a collar 2 on the laterally-projecting portion of the standard B, said collar having a set screw 3, or other suitable means, for clamping the member C in 60 adjusted position. It is immaterial how the base and the standard B are constructed, but I prefer to form said parts from metal and integrally connect them together, either the base or the standard being provided 65 with means for securing the can opener to a supporting structure. In the form of my invention herein shown the standard B is substantially T-shaped in horizontal cross section, and one flange of same is provided 70 with holes 4 for receiving screws or other suitable fastening devices that secure the can opener to a wall or upright.

The member C is provided at its lower end with a piercing point 5 that penetrates 80 the head of the can when the member C is forced downwardly, and a shoulder 6 is formed on the member C at the base of the piercing point 5, so as to form a flat bearing 85 surface that will engage the top face of the head of the can, and thus securely clamp the can on the base A. If desired, the piercing point 5 may be provided with a notch 5^a, as shown in Fig. 2, so as to prevent the severed head of the can from slipping off 90 the piercing point 5 when the member C is moved upwardly, after the operation of opening the can has been completed.

An arm D that is revolvably mounted on the vertically-disposed member C is provided with a knife blade or cutting device 7 for severing the head of the can, said cutting device being preferably adjustably mounted on the arm D so that it can be moved toward and away from the axis 100 about which the arm D swings in a horizontal direction, and thus enable the device to be used for opening cans of various sizes. In the preferred form of my invention, as herein shown, the device 7 is provided with 105 a V-shaped piercing point which is flat on its inner vertical side, as shown in Fig. 1, and curved on its outer side, as shown in Fig. 2, thus forming a double-edged cutting device that will turn over the edge of the 110 opening that is formed in the head of the can by removing the center portion of the

head. The device 7 is slidably mounted on the arm D and it is provided with a set screw, or other suitable device 8, for clamping it in adjusted position. Instead of 5 mounting the arm D directly on the member C, I prefer to mount said arm on a bearing E that is revolubly mounted on the member C in proximity to the lower end thereof, said arm being connected to the 10 bearing E in such a manner that the arm and the cutting device 7 thereon can be moved vertically with relation to the can-holding member C. The bearing E is retained in operative position on the member 15 C by means of two cross pins 9 on the member C that are arranged above and below the bearing E, and the arm D is pivotally connected to a lateral extension 10 on the bearing E that projects laterally some distance 20 from the can-holding member C, as shown in Fig. 3. The purpose of mounting the arm D in this manner is to insure the cutting device 7 traveling in a substantially vertical path when it enters the head of 25 the can, during the first part of the operation of opening the can, the lateral projection 10 on the bearing E making it possible to use a comparatively long arm D to carry the cutting device. The arm D is provided 30 with a bifurcated portion 11 that straddles the bearing E, and said parts are pivotally connected together by a horizontally-disposed pin 12 that passes through same some distance from the vertical axis about which 35 the bearing E revolves.

A means is provided for normally holding the free end of the arm D in a slightly elevated position and for automatically moving the cutting device 7 out of engagement 40 with the head of the can when the operator releases the arm D. This can be accomplished in various ways, but in the embodiment of my invention herein illustrated a coiled spring 13 is used for normally holding the arm D in an upwardly-inclined position, as shown in Fig. 1, said spring 13 being mounted on the pintle pin 12 in a notch 14 formed in the bearing E, and having its opposite ends arranged in 45 engagement with the bearing E and with a bracket 15 that projects forwardly from one of the side pieces of the bifurcated portion of the arm D.

To open a can with a can opener of the 55 construction above described, the operator arranges the can on the base A and then moves the member C downwardly, so that the piercing point at the lower end of same will penetrate the head of the can, and thus 60 center the can in operative position on the base A of the device, the set screw 3 being thereafter tightened, so as to retain the member C in adjusted position. After the cutting device 7 has been set in proper position 65 on the arm D, the free end of said

arm is moved downwardly, so as to cause the cutting device 7 to penetrate the head of the can, and thereafter said arm D is swung in a horizontal plane, so as to form a cut in the head of the can concentric with 70 the vertically-disposed can-holding member C, the operator turning the can progressively as the cutting operation continues, so as to completely sever the center portion of the head of the can. As soon 75 as the operator releases the free end of the arm D, the spring 13 will move said arm upwardly, and thus disengage the cutting device 7 from the head of the can. After the set screw 3 has been loosened, the 80 member C can be moved upwardly, so that it will clear the upper edge of the can, the notch in the piercing point at the lower end of said member operating to prevent the severed portion of the head from dropping 85 downwardly into the can.

With a can opener of the construction above described very little pressure is required to form the initial cut in the head of the can, owing to the fact that the cutting 90 device is not forced into the head of the can until after the can has been centered by forcing the piercing point on the member C through the head. Still another desirable feature of such a can opener is that the cutting device is carried by a comparatively long arm which is pivotally mounted in such a manner that the cutting device travels in practically a vertical path when it penetrates the head of the can to form the initial 95 cut, thus enabling the cutting device to easily penetrate the head of the can, when the operator exerts a slight downward pressure on the arm D. The fact that the cutting device is moved automatically out of 100 engagement with the head of the can as soon as the arm D is released, is a desirable feature of my improved can opener, and the fact that the device 7 forms a clean cut with a turned over edge, is also another very 105 desirable feature. In addition to the desirable features above mentioned, my improved can opener can be manufactured cheaply, on account of its simplicity of construction, the parts being so designed that they can be 110 formed easily from cast metal or from sheet metal stampings and assembled with practically no machine work.

Having thus described my invention, what I claim, and desire to secure by Letters Patent, is:

1. A can opener, comprising a vertically-disposed member that is adapted to be moved into engagement with the head of a can to center the can, an arm revolubly mounted on said member and provided with a cutting device for severing the head of the can, said arm being pivotally mounted, and means that tends to hold the free end of said arm in an elevated position.

2. A can opener, comprising a vertically-disposed member that is adapted to be moved into engagement with the head of a can to center the can, a vertically-swinging arm revolvably mounted on said member and provided with a device for severing the head of the can, and resilient means that causes the free end of said arm to be normally held in an elevated position. 5
- 10 3. A can opener, comprising a vertically-disposed member that is adapted to be moved into engagement with the head of a can to center the can, a bearing revolvably mounted on said member, a vertically-swinging arm pivotally connected to a lateral extension on said bearing and provided with a cutting device for severing the head of the can, and means that tends to hold the free end of said arm in an elevated position. 15
- 20 4. A can opener, comprising a vertically-disposed member that is adapted to be moved into engagement with the head of a can, a bearing on said member that can turn thereon, a member joined to said bearing by a pivotal connection which permits said member to swing about a horizontal axis, and a cutting device on said member that enters the head of the can and forms a circular cut in same when the free end of said 25 member is depressed and then swung in a horizontal plane. 30
5. A can opener, comprising a vertically-disposed member that is adapted to be moved into engagement with the head of a can, a bearing on said member that can turn in a horizontal plane, a vertically swinging arm having a portion that straddles said bearing and which is joined to same by a horizontally-disposed pivotal connection, 35 and a cutting device on said arm. 40
6. A can opener, comprising a vertically-disposed can-centering member, a revolvable bearing on said member provided with a
- lateral extension, a vertically-swinging arm having a bifurcated portion that straddles 45 said bearing and which is joined to said extension by a pivotal connection which permits said arm to swing about a horizontally-disposed axis, and a cutting device on said arm. 50
7. A can opener, comprising a vertically-disposed can-centering member, a revolvable bearing on said member provided with a lateral extension, a vertically-swinging arm having a bifurcated portion that straddles 55 said bearing and which is connected to said extension, a cutting device on said arm, and a coiled spring arranged in engagement with said bearing and with the bifurcated portion of said arm for normally holding 60 the free end of said arm in an elevated position. 65
8. A can opener, comprising a base provided with a standard, a vertically-adjustable member carried by said standard and provided at its lower end with a piercing point and with a flat surface that is adapted to bear on the top face of the head of a can, a revolvable bearing on said member provided with a lateral extension, a vertically-movable arm provided with a cutting device, 70 a bifurcated portion on said arm that straddles said bearing and which is pivotally connected to the extension on said bearing, and a coiled spring arranged in a notch in 75 said extension with one of its ends in engagement with said bearing and with its opposite end in engagement with a bracket on the bifurcated portion of said arm. 80

In testimony whereof I hereunto affix my signature in the presence of two witnesses, this eleventh day of February, 1916.

WILLIAM P. GRUNER.
